PNEUMATIC ROLLER

Jack B. Peterson, Portland, Oreg., assignor to Hyster
Company, Portland, Oreg., a corporation of Nevada

Filed Jan. 22, 1962, Ser. No. 68,403

Term of patent 14 years

(Cl. D14—3)

Fig. 1

Fig. 2

Fig. 3

Fig. 4

FIG. 1 is a side view of a pneumatic roller showing my new design;

FIG. 2 is a top view thereof;

FIG. 3 is a right front perspective view thereof; and
FIG. 4 is a left rear perspective view thereof.

I claim:
The ornamental design for a pneumatic roller, as shown.
